UNITED STATES PATENT OFFICE

WALTER C. FELLOWS, OF PHILADELPHIA, PENNSYLVANIA, ASSIGNOR TO C. R. CARVER COMPANY, A CORPORATION OF PENNSYLVANIA

EMBOSSING AND PRINTING PRESS

Application filed October 30, 1928. Serial No. 315,973.

Embossing and printing presses, sometimes designated as stamping presses, have usually been constructed with a reciprocating die carrying slide the movement of which 5 brings the die successively in contact with the inking roller and wiper, and thereafter positions the die face upward under the plunger and by means of which the paper sheet is pressed downward upon the die, the 10 printing impression being imparted to the sheet while in an inverted position. This procedure requires care in handling the printed sheets to avoid smudging, and also requires them to be inverted after being 15 withdrawn from the action of the die and plunger.

The object of my present invention is to enable the printing to be performed upon the upper surface of the sheet and in full 20 view when the sheet is withdrawn from the die and plunger and removed to the receiving table without the necessity of inverting it, thereby simplifying the manual labor, avoiding danger of smudging the printed 25 sheets, and permitting increased capacity to the press.

In carrying out my invention, I provide the upper portion of the housing with arcuate shaped guides and combine therewith a 30 slide equipped with a die carrying chuck, the latter arranged upon the underside of the slide; the said arcuate shaped guides extending from the rear of the press forward to a position between a stationary inverted bed 35 and a vertically reciprocable plunger arranged in alinement with the bed and below the guides, the said reciprocating plunger being suitably operated, as by toggle and cam mechanism, in unison with suitable 40 power applying means which position the die carrying slide in definite position above the plunger preliminary to the upward thrust thereof.

My invention further comprises in a press 45 of the character described, means whereby the chuck carrying slide is reciprocated through the curved guides and is automatically locked in fixed relation to the bed when properly positioned above the reciprocating plunger, to prevent any shifting of

the slide and die carried thereby relatively to the plunger during the printing or embossing operation.

Further improvements comprised in my invention relate to special means for inking the inverted die in the custody of the slide, the scraping or removal of the surplus ink from the surface of the die, and the wiping of the surface of the die before the printing impression, said operations taking place successively during the advancing travel of the slide and the die carried thereby through the arcuate shaped guides.

My invention also comprehends other and special features of improvements which, together with those above enumerated, are fully described hereinafter and more particularly pointed out in the claims.

Referring to the drawings: Fig. 1 is a rear elevation of a printing press embodying my improvements; Fig. 2 is a vertical section of the same taken on line 2—2 of Fig. 1; Fig. 3 is a perspective view of a portion of the adjusting means for controlling the degree of pressure applied during the printing operation; Fig. 4 is a plan view of the same, and partly in section taken on line 4—4 of Fig. 2; Fig. 5 is a rear view of the wiper mechanism separated from the press; Fig. 6 is a transverse vertical section of the same taken on line 6—6 of Fig. 5; and Fig. 7 is a perspective view illustrating the locking means for holding the die carrying slide against movement during the embossing or printing operation.

The main side frames or housings of the machine are indicated at 2 and are united at their forward portions by the upper transverse front or bed carrying frame 3 and by the lower front base frame 5. The lower base frame 5 is provided with upwardly extending heavy bolts 4, 4, secured at the bottom in hubs 4a and also clamped to the upper portion of said base frame by clamping means 4b. The upper bed frame 3 is provided at its sides with heavy clamping hubs 3a which fit over the aforesaid bolts 4, and when adjusted to proper positions upon the bolts, the upward thrust during the printing action is resisted by nuts 4c upon the upper

ends of the bolts. This provides a two-part front structure, the upper of which includes the bed 6 which receives the upward thrust of the die carriage or slide 7 during the printing or embossing operation, whereas the lower bed frame 5 is provided with the vertically reciprocating plunger 8 and the toggle mechanism 9 by which it is reciprocated. These upper and lower front frame portions 3 and 5, while bolted together in definite relative positions one above the other, are both secured to the side frames 2, 2, by cap screws indicated in dotted lines at 2a in Fig. 1.

10 are rearwardly extending arcuate 15 grooved guides, the lower forward ends of which extend to the rear portions of the bed 6 and in which the slide 7 is guided, whereby it may assume a position directly under the bed 6 or various positions to the rear of said 20 bed during its reciprocation, as indicated in dotted lines in Fig. 2. These guides, preferably, are arc-shaped about the axis of the rockshaft 11 journaled in suitable bearings 11a on the upper portion of the front frame 25 3. Secured to the rockshaft 11 is an arm 12 whose lower end terminates a short distance from the guides 10. The slide 7 is provided with lateral curved guide portions 7a which snugly fit the curved guide grooves of the 30 arcuate guides 10 and provide means whereby said slide is accurately guided during its rearward and forward reciprocations under the action of the arm 12. The slide 7 is connected with the lower end of the arm 12 by means 35 of a toggle comprising links 13 and 14 hinged together at 15. The link 14 is hinged to the arm 12 at 16 and the link 13 is hinged to the slide 7 at 17. The toggle has its hinged portion 15 provided on each side with rollers 40 15a which are guided in arcuate guides 18 of less radius than the arcuate guides 10 for the slide, and which guides 18 also have a curvature with the axis of the rockshaft 11 as a center. The forward ends of the guides 45 18 terminate in a reverse curved portion 18a, the extreme forward end of which is shaped with a curvature concentric with the axis of the hinge 17 forming the connection between the link 13 and the slide 7. The result of 50 this connection and the shape of these guides is, that when the slide 7 is in its forward or printing position, the link 13 is free to swing upwardly about the hinge 17 without moving the slide during the final forward swinging 55 of the arm 12, but which, during the rearward swinging of said arm, will permit the toggle links 13 and 14 to straighten out preliminary to moving the slide backward as indicated in dotted lines in Fig. 2. During the main 60 oscillations of the arm 12, the slide 7 is reciprocated in its arcuate guides 10, but in the final forward movement of the arm 12 and when the toggle assumes the position indicated in Fig. 2, the portion 13 of said toggle 65 operates to lock the slide in its printing posi-

tion and retain it so locked during the actual printing or embossing. This locking may be performed in any suitable manner, but the means shown has been found satisfactory in practice.

The particular locking mechanism shown comprises a stud 19 fixedly secured to one of the guide frames 18 or other fixed part of the machine and having a horizontal flattened portion 19a, and a hinge shaft 17 provided with a head 20 having two curved wing portions 20a which in locking position enclose between them the flattened portion 19a of the stud (Figs. 2 and 7), and in that manner prevent the slide from having any movement forward or backward, it being understood that the shaft 17 is secured to and positively rocked with the link 13 of the toggle. When the arm 12 is moved rearwardly, the first action is to cause the toggle link 13 to swing rearwardly about the axis of the shaft 17, and in so doing, the shaft rotates the head 20 and moves the wing portions 20a to positions above and below the flattened portion 19a of the stud, with the result that the locking relation therewith has been put out of action and the continued rearward motion of the arm 12 through the straightened toggle is free to move the slide 7 rearwardly. In this manner, the slide is free to move at all times, except when in its forward position as indicated in Fig. 2, and at which time it is definitely locked.

The arrangement of the arcuate slide guides and the concentric or tram guides for the rollers of the toggle have advantages in the following particulars: The slide guides, being on a curve concentric with the axis of the rockshaft 11, will cause the slide and its die to move backward and upward in such a manner as to bring the plane of the die to approximately 45°, thereby allowing the operator to clean the die more readily and also to examine the same from time to time in case of defects. Moreover, the guide rollers 15a of the toggle are caused to travel in the guides 18 in such a manner as to move through said guides with the least possible resistance, the thrust or pull upon the guide rollers being in a line substantially tangent to the curvature of the guide. Furthermore, the couple through the toggle is such that the slide 7 is caused to press upon the upper flange of the arcuate guide 10 during its backward movement, due to the tendency of the pull through the toggle to straighten the same and lift the slide. The use of the curved guides 18 in association with the arcuate guides 10, insures the toggle links 13 and 14 being maintained in an alinement to cause the slide to be properly reciprocated to bring the die and slide back to a horizontal position and up to a registered point, wherein it is locked, and wherein further, a steady smooth motion to the slide in the course of its travel is definitely assured.

In view of the pull of the slide in its backward movement, causing its guides 7a to press against the upper inward flange of the arcuate guides 10, it is desirable that these guides shall be made of a main part 10a of angle shape in cross section and closed on its rear and underside by a curved cap plate 10b, the latter being detachably secured in place by screws.

10 The die carrying slide 7 is so shaped that during the printing operation it rests flat against the bed 6 and at this time the lateral guide portions 7a of the slide should not fit tightly or bind in the guide grooves of the arcuate guides, the said guides only being intended to accurately guide the slide during the act of inking, scraping and wiping of the die, and insuring the proper positioning of the slide when it reaches the horizontal bed 6.

25 21 represents the die chuck secured to the underside of and movable with the slide 7 and carries the die 22 which may be secured in the chuck in any of the usual manners. The printing surface of the die is directed downward and cooperates with the counter block 23 carried at the upper end of the reciprocating plunger 8.

The reciprocating plunger is a box-like structure movable in vertical guides 8a and 30 having in its upper portion a plunger block 24 upon which the counter block 23 is directly positioned, and by which it is moved. The plunger block 24 is connected to the plunger 8 by means of a horizontally adjustable wedge 25, the adjustment of which provides the desired printing pressure. The wedge block has lateral flanges 25a which fit into grooves 25b in the plunger block 24, and the wedge has also on its lower part flanges 35 25c which fit into corresponding grooves 25e in the plunger 8. In this manner, the plunger, the wedge and the plunger block maintain their connection while permitting the latter to be raised and lowered to a slight extent due to the lateral adjustment of the wedge.

40 To adjust the wedge of the plunger the following construction, best shown in Figs. 2, 3 and 4, is employed. 26 is a frame or bracket attached to the plunger block 24 and, therefore, movable vertically with it. This bracket in addition to supporting the middle table 27 immediately in front of the counter block and die when in printing position, also has journaled in it two adjusting screws 28, the rotation of which causes the wedge to be moved horizontally in either direction so as to raise or lower the plunger block and its counter block, according to the direction of rotation of the screws. These screws are provided with gears 29 which mesh with a gear 30 on a central shaft 31. The rotation of the shaft 31 will, through the gears, simultaneously rotate the screw shafts and in that manner secure the adjustment 45 of the wedge.

32 is a universally jointed operating spindle for rotating the central shaft and is provided with capacity to control the central shaft from a point to one side of the plunger. In presses of this character, the table portion in front of the plunger is made in three parts, shown in dotted lines at 27a, 27, and 27b, the middle part 27 ordinarily being removable. In Fig. 4, I have shown the 70 jointed spindle and operating hand wheel projecting directly in front of the plunger, as it would be if the bracket 33 were secured to the bottom of the middle or removable part of the table. Instead of securing the bracket to the middle table, I prefer to attach it to either one of the lateral tables 27a or 27b, and by illustration of such use, I have shown, in dotted lines in Fig. 4, the universally jointed spindle 32 extending obliquely from the shaft 31 and connecting with the adjustable hand wheel 34 journaled in the bracket 33 attached to the fixed side table 27a.

75 In this manner, the hand operated means for adjusting the wedge 25 may be definitely positioned upon the stationary table portion 27a of the machine, while the central shaft 31 may be rotated for adjusting the wedge. Moreover, this construction maintains a constantly operative means for adjusting the wedge and without interference with the removal of the center table 27 when closer access is required to the front of the machine. It is manifest that with this construction, the extent of the impression pressure may be accurately adjusted to suit the character of printing and the material employed upon which the embossing or printing is performed; and this adjustment, whether to increase the pressure or decrease the same, may be adjusted while the machine is in operating condition, and if desired, during the actual performance of the printing or embossing operation.

80 Furthermore, as the plunger is reciprocated by the toggle 9, it is manifest that the wedge 25 will be reciprocated with it, and this will be possible due to the fact that the universal connection 32 is flexible so as to permit such reciprocations without disturbing the bracket 33 or the hand wheel journaled therein, and which bracket is connected to a stationary part of the machine. By means of this construction, the upper level of the central table 27 may be arranged 85 on exact level with the counter and counter block 23, so that the paper may be readily fed into position, notwithstanding that the counter block is vertically reciprocated under the action of the toggle 9.

90 The toggle 9 may be of any usual construction. As shown, it includes an oscillating member 9a which is hinged at 9b to a frame 35 sliding upon a box 36 journaled upon the bull gear shaft 37, and said shaft also having 95

a cam 38 which co-acts with rollers 39 and 40 to reciprocate the frame 35 and oscillating member 9a of the toggle. The bull shaft 37 is geared to operate in unison with the mechanism which reciprocates the slide and die carried thereby. As indicated, the bull shaft is provided with a bull gear 41 which is driven by a pinion 42 of a shaft 43, the latter being, in turn, driven by speed reducing gears 44 and 10 a power shaft 45 having a belt wheel or other means for driving it, as is employed in presses of this character.

47 is a rockshaft at the rear of the machine and is rocked by an arm 48 having at its free 15 end a hook shaped link 49 adapted to make a detachable connection with a crank pin 50 on the bull gear. In this manner, the rockshaft 47 is oscillated in timed relation with the toggle which operates the plunger. The 20 rockshaft 47 is provided with a short arm 51 having a link connection 52 which extends upwardly and hinged to an arm 53 on the rockshaft 11 to which the arm 12 is secured and by which it is oscillated for reciprocating 25 the slide and the die carried thereby. By these means, the movement of the slide 7 and the vertically adjustable plunger 8 and its operating means are caused to operate simultaneously in timed relation.

30 The parts as shown in Fig. 2, are just in the middle of making a printing impression and wherein the slide 7 with its attached die 22 receives the upward thrust of the plunger 8 with its counter plate 23 under the action 35 of the toggle mechanism 9.

In addition to the construction and operation already described, there are three additional functions to be performed, namely, the 40 application of ink to the die, scraping the surplus ink from the die and returning it to the fount, and the wiping of the printing surface of the die before the act of printing. I will consider these three functions and the means employed for carrying them into effect.

45 54 is the ink fount and 55 is the ink applying roller for distributing the ink to the surface of the die 22. The inking roll 55 is journaled in the free end of oscillating arms or frames 56 secured to a rockshaft 57 and 50 during the rocking of which the inking roll swings from the fount to contact with the die plate, as shown in dotted lines (Fig. 2) and back again to the ink well or fount. The oscillation of the rockshaft 57 for actuating the ink roll and the oscillation of the rockshaft 11 for reciprocating the slide and its die are caused to operate in timed relation whereby the ink is applied to the die at or about the 55 time the same begins its forward travel.

As a means for oscillating the rockshaft 57, I provide an arm 58 secured thereto which connects by a link 59 with a pivoted lever 60 adapted to be actuated by a cam 61 secured to 65 and rotating with the bull shaft 37, and

whereby the rockshaft 57 has one oscillation to each revolution of the bull shaft.

Referring now to the scraper means for removing the surplus ink from the inked die and returning it to the ink fount or well, I provide the following construction. 62 is an oscillating frame journaled upon a shaft 63, the frame having upwardly projecting sides 64 and surface plates between the side edges, one of which, 65, projects upwardly for contact with the inked die during its advancing movement as indicated in Fig. 2, and the other of which plates, 66, extends rearwardly in the form of a shallow gutter for delivering the surplus ink back into the ink well or fount 80 54. The extent of the oscillations of the scraper frame 62 is limited by a frame 67 extending from a fixed part of the machine and limiting the movement of the oscillating frame 62 to a very small extent, the purpose 85 being to normally hold the scraper blade 65 in a position which would lightly scrape the surface of the die when the slide was moving forward into printing position, and at the same time to limit the extent of movement 90 away from the die plate so as to be out of contact with it when the slide and the plate is being moved rearwardly to receive ink. A very slight movement, therefore, will suffice 95 for the needs of the frame 62.

A coil spring 68 extending around the shaft 63 has one end fastened to the main frame of the machine and the other end fastened to the scraper frame 62 for normally oscillating the frame 62 and scraper to bring the latter into 100 contact with the moving printing die when not otherwise held out of such contact by means now to be described.

The shaft 63 to which the scraper frame 62 is secured is journaled in the side frames 105 or housings 2 and has at one end an arm 69 having a block 70 pivoted thereto and through which a rod 71 slidably extends with a spring 72 interposed between the end of the rod and the said pivoted block. The 110 other end of the rod 71 is hinged to an arm 73 secured to the rockshaft 57, heretofore referred to in connection with the movements of the inking roll.

It will now be understood that when the 115 inking roll is moved to its dotted position in Fig. 2, the rocking of the shaft 57 causes the rod 71 to be pulled longitudinally and thereby, through the spring 72, cause the scraper frame 62 to be oscillated (overcoming the 120 action of the spring 68) and causing the scraper 65 to be moved downward to permit the rearward travel of the slide 7 and printing die 22. When the advancing movement of the slide and its printing plate takes place 125 and after the ink has been applied to the printing plate, the rockshaft 57 is given a movement under the action of cam 61, with the result that the scraper frame 62 is allowed to oscillate until stopped by the abut- 130

ment 67, and is then in position to enable its scraper 65 to provide a scraping action upon the surface of the die to remove the surplus ink, said scraping action being a yielding one under the influence of the coil spring 68 before referred to, and during that action, it is out of contact with the abutment 67.

From these explanations, it will be understood that the inking device and the scraping device are under the control of the same general actuating means and hence in timed relation. Aside from the oscillating action of the scraper, it has a traversing motion laterally with respect to the direction of travel of the printing die. In other words, the shaft 63 is given a slight longitudinal reciprocation to improve the scraping action of the scraper blade 65 and this reciprocation is accomplished by a bell-crank 74 acting upon the shaft and, in turn, oscillated by a pitman rod 75 pivoted at its lower end to a crank 76 which is driven by a worm wheel 77 meshing with a worm 78 on the power shaft 45, as indicated in Fig. 1.

As before stated, the printing or embossing die 22 must have its surface wiped clean after the surplus ink is scraped off, and this wiping action is performed by the following means. 79 is the wiper bracket and is secured to a rockshaft 18 journaled in the main frame and below the arcuate guides for the reciprocating slide. The said shaft 80 is provided with a crank arm 81 to which is pivoted a link 82, the lower end of which is hinged to a pivoted arm 83, said arm 83 having a roller 84 extending into a cam groove 85, of a cam 86 secured to the bull shaft 37. By this means, the proper oscillating motion is given to the wiper bracket 79. Hinged to the upper part of the bracket 79 is a wiper plate 87, said wiper plate secured to a shaft 88 journaled in the bracket 79 as clearly shown in Figs. 5 and 6. The curved face 87a of the pivoted wiping plate 87 is eccentric to the shafts 80 and 88, but the eccentricity of said surface with respect to the rockshaft 80 may be adjusted so as to be increased or decreased according to requirements. The means for effecting such adjustment will be best understood by reference to Figs. 5 and 6.

The shaft 88 which carries the wiping plate 87 is provided with a segmental rack 89 which is actuated by a worm 90 to change the eccentricity of the wiper plate in respect to the rockshaft 80. The worm 90 is extended into a shaft 91 journaled in bearings 92 on the bracket 79, and said shaft 91 is provided with a worm wheel 93 which is adjusted by a worm 94 having a shaft 95 journaled in bearings 96 secured to the bracket 79 and adapted to be adjusted by a suitable key. In this manner, the eccentric wiping plate 87 may be given slight and accurate adjustments and at

the same time is positively held upon the bracket 79 in its adjusted positions.

The eccentric wiping plate 87 is covered or faced with a blanket or padded portion 97 which may be clamped at one end of the wiping surface and stretched at the other end by a ratchet and pawl take-up shaft 99 arranged under the wiping plate at the other end. The position of this wiping mechanism on the press and in respect to the path of the reciprocating slide and die is clearly indicated in Fig. 2.

100 represents the web of wiping paper which is led from the roll 101 at the rear of the machine, thence between feed rolls 102, thence about a guide rod or roll 103, thence about the wiping plate 87, thence rearwardly to the winding mandrel 104, which latter may be driven by the usual friction or take-up drive (not shown). The manner of feeding the paper web about the wiper and to the take-up mandrel may be made to correspond to the usual practice heretofore in use.

The wiping plate 87 is arranged to move in the opposite direction to the movement of the die 22 when the die is moving forward toward its printing position, and the oscillation of the eccentric surface of the wiper plate about the axis of the rockshaft 80 keeps bringing fresh surfaces of the paper in contact with the inked surface of the die so that a perfect and clean wiping results.

It will be understood that the arcuate shaped guides 10 cause the slide plate and the die carried thereby to constantly change the presentation of the inked surface of the die as it moves forward, and the eccentricity of the wiping plate and surface of the wiper compensate for this changing angle or inclination of the inked die as it moves forward. This will be understood by referring to Fig. 2 and noting that the forward end of the die 22 is about to come into contact with the rearward end of the eccentric wiping surface, and with the further understanding that as the die moves forward, it tends to gradually approach a horizontal alignment, and wherein the printing surface gradually recedes from the axis of the rockshaft 80, and which receding is compensated for by the advancing wiping surface due to the eccentricity of the wiping plate. It will be further understood that when the slide and die is moving rearwardly, the wiper is out of contact with the die and will retain this inactive position (Fig. 2) while the bull shaft 37 makes approximately three-quarters of a revolution. The oscillation of the wiper in a rearward direction only takes place when the slide and die are moving forward over it, and thereafter the wiper returns to its initial position shown in Fig. 2, while the slide and die performs the printing operation and moves rearwardly for re-inking and advancing again to the left hand dotted position shown in Fig. 2.

It will now be apparent that I have devised a novel and useful construction which embodies the features of advantage enumerated as desirable, and while I have in the present instance shown and described the preferred embodiment thereof which has been found in practice to give satisfactory and reliable results, it is to be understood that I do not restrict myself to the details as the same are susceptible of modification in various particulars, without departing from the spirit or scope of the invention.

Having now described my invention, what I claim and desire to secure by Letters Patent is:

1. In a press of the character stated, the combination of vertical guiding means, a stationary head above the said guiding means and formed on its underside with a bed, rearwardly extending arcuate shaped guides terminating at the forward ends in the head adjacent to the bed and having the rearward portions curved upwardly, a die carrying slide having lateral guides adapted to the arcuate shaped guides whereby the slide may be reciprocated from a position immediately below the head and bed thereof to a rearward position, power means for reciprocating the slide, a vertically reciprocating plunger guided in the vertical guides, and power means for reciprocating the plunger connected in timed relation with the power means for reciprocating the slide.

2. The invention according to claim 1, wherein further, the power means for reciprocating the slide comprises a rockshaft located at substantially the center of curvature of the rearwardly extending arcuate shaped guides, an oscillating arm secured to the rockshaft and having its free end extended toward and close to the arcuate shaped guides, a jointed connection between the movable end of the arm and the slide, and means for holding the jointed connection in an extended manner while reciprocating the slide and releasing it during the final motion of the arm whereby said final motion is permitted without further movement to the slide.

3. The invention according to claim 1, wherein further, locking means are provided for locking the slide in its printing position between the bed and the plunger, and means actuated by the power means which reciprocates the slide for operating the locking means to put it into locking position when the slide has reached the end of its forward movement.

4. The invention according to claim 1, wherein the power means includes an oscillating arm and locking means for holding the slide against movement when in inverted printing position, said locking means comprising a rocking arm hinged to the slide and having a locking portion making locking engagement with a fixed portion of the press,

a link connection between the free end of the rocking arm and the free end of the oscillating arm, and a guiding means for holding the rocking arm and link in substantial alignment during the reciprocation of the slide, said guiding means shaped to permit the jointed connection between the rocking arm and link to fold after the slide has been moved to its printing position and during the final movement of the oscillating arm in bringing the locking means into locked position.

5. The invention according to claim 1, wherein the plunger is provided with means for adjusting the printing pressure, said means comprising a box-like plunger body, an upper plunger block carrying a counter block, a wedge engaging the body and plunger block for adjusting the latter vertically with respect to the former, two parallel screw shafts engaging the adjustable wedge for adjusting it, a central shaft intermediate of the screw threaded shafts and geared to each of them, a bracket at a distance from the wedge and provided with a manually adjustable shaft and wheel, and a universally jointed connection between the said shaft and wheel and the intermediate shaft which is geared to the screw threaded shafts, whereby said manually adjustable wheel and shaft may be arranged out of alignment with the geared shaft while maintaining its operative relation thereto.

6. The invention according to claim 1, wherein further, means are provided for distributing ink upon the under or printing surface of the die carried with the slide, an oscillating wiper pivoted on a horizontal axis and having an eccentrically arranged and upwardly presented wiping surface, means for oscillating the wiper, and a traveling web of wiping material intermittently fed over its surface, said wiper positioned to wipe the downwardly presented inked surface of the die.

7. The invention according to claim 1, wherein further, means are provided for distributing ink upon the under or printing surface of the die carried with the slide, an oscillating wiper pivoted on a horizontal axis and having an eccentrically arranged and upwardly presented wiping surface, means for oscillating the wiper, and a traveling web of wiping material intermittently fed over its surface, said wiper positioned to wipe the downwardly presented inked surface of the die, and wherein also manually adjustable means are provided for modifying the extent of the eccentricity of the wiping surface of the wiper.

8. The invention according to claim 1, wherein further, an ink fountain and means are provided for distributing ink to the die and removing the surplus ink therefrom prior to

the printing operation, said means for removing the surplus ink including a scraper having a pivoted frame arranged for oscillation upon a horizontal transverse shaft and having also extending upwardly forward of the shaft a scraper blade arranged to scrape the under surface of the traveling die when advancing to printing position and said scraper further having an extension rearward of the shaft and obliquely downward for returning the surplus ink to the ink fount by gravity, spring devices for causing the scraping of the surplus ink to be performed under a yielding pressure by the scraper blade upon the die, and positively acting means to oscillate the scraper for moving it out of scraping action when the slide and die are moving rearwardly into inking position.

9. The invention according to claim 1, wherein further, an ink fount and means are provided for distributing ink to the die and removing the surplus ink therefrom prior to the printing operation, said means for removing the surplus ink including a scraper having a pivoted frame arranged for oscillation upon a horizontal transverse shaft and having also extending upwardly forward of the shaft a scraper blade arranged to scrape the under surface of the traveling die when advancing to printing position and said scraper further having an extension rearward of the shaft and obliquely downward for returning the surplus ink to the ink fount by gravity, spring devices for causing the scraping of the surplus ink to be performed under a yielding pressure by the scraper blade upon the die, and positively acting means to oscillate the scraper for moving it out of scraping action when the slide and die are moving rearwardly into inking position, and wherein also the oscillating scraper is combined with power means for causing the scraper blade to be slowly traversed back and forth longitudinally of its axis of oscillation during contact with the die plate.

10. The invention according to claim 1, wherein further, the arcuate shaped guides for guiding the slide are each formed of an angle shape in cross section with the integral angular portions closing the top and outer lateral sides of the guides, and removable curved cap plates are secured to the outer lateral side portions of the guides to hold the guiding portions of the slide from disengagement with the guides.

11. The invention according to claim 1, wherein the plunger is provided with adjustable devices moving with the plunger for adjusting the level of its impression surface relatively to the plunger body for varying the pressure of the impression, a removable feeding table in front of the plunger, hand operable means supported at one side of the plunger

and independent of the table, and adjustable power transmitting means connecting the hand operable means with the adjustable devices for adjusting the level of the impression surface.

12. In a press of the character stated, the combination of a vertical guiding means, a stationary head above the said guiding means and formed on its underside with a bed, rearwardly extending guides terminating at their forward ends in the head adjacent to the bed, a die carrying slide movable in the guides and presenting the face of the die in a downward direction above the vertical guiding means, a plunger with adjustable devices moving with the plunger for adjusting the level of its impression surface relatively to the plunger body for varying the pressure of the impression, hand operable means supported at one side of the plunger and universally adjustable power transmitting means connecting the hand operable means with the adjustable devices for adjusting the level of the impression surface.

13. The invention according to claim 12, wherein further, the adjustable devices comprise a wedge and a screw for adjusting it, and wherein also, the power transmitting means includes a universally jointed shaft at one end mechanically connected with the screw to rotate it and at the other end with the hand operable means.

14. In a press of the character stated, the combination of a reciprocating die carrying means and die therefor, means for applying ink to the die surface, a scraper pivoted on a transverse axis and adapted to scrape the surplus ink from the die surface, a spring actuated means for moving the scraper into yielding contact with the surface of the die when moving in one direction, positively acting means for moving the means for applying ink to the die surface and for alternately therewith moving the scraper out of scraping contact with the die surface.

15. In a press of the character stated, the combination of a reciprocating die carrying means and die therefor, means for applying ink to the die surface, a scraper pivoted on a transverse axis and adapted to scrape the surplus ink from the die surface, said scraping action taking place alternately and subsequently to the application of ink to the die surface, a stop, continuously acting spring means for normally moving the scraper yielding against the stop to enable the scraper to yieldingly make scraping contact with the surface of the die when said die is moving in the direction toward its printing position, means for applying power to the scraper for positively moving it away from the stop and out of scraping relation with the surface of the die when said die is moving in the other direction away from its printing position,

said means providing a yielding connection with the scraper whereby it may hold the scraper out of scraping position during the period of applying ink to the die surface.

5 In testimony of which invention, I hereunto set my hand.

WALTER. C. FELLOWS.
